(57) **CLAIM**

The ornamental design for a playground platform rocker, substantially as shown and described.

DESCRIPTION

FIG. 1 is a perspective view from above of a playground platform rocker according to the present invention and shown positioned in the exemplary environment of a playground structure with a rider thereon;

FIG. 2 is a front side elevation view of the playground platform rocker of FIG. 1;

FIG. 3 is a rear side elevation view of the playground platform rocker of FIG. 1;

FIG. 4 is a right side elevation view of the playground platform rocker of FIG. 1;

FIG. 5 is a left side elevation view of the playground platform rocker of FIG. 1;

FIG. 6 is a top plan view of the playground platform rocker of FIG. 1; and

FIG. 7 is a bottom plan view of the playground platform rocker of FIG. 1;

FIG. 8 is a perspective view from above of a playground platform rocker according to the present invention and shown positioned in the exemplary environment of a playground structure with a rider thereon;

FIG. 9 is a left side elevation view of the playground platform rocker of FIG. 8;

FIG. 10 is a right side elevation view of the playground platform rocker of FIG. 8;

FIG. 11 is a front side elevation view of the playground platform rocker of FIG. 8;

FIG. 12 is a rear side elevation view of the playground platform rocker of FIG. 8;

FIG. 13 is a top plan view of the playground platform rocker of FIG. 8;

FIG. 14 is a bottom plan view of the playground platform rocker of FIG. 8; and,

FIG. 15 is a perspective view from below of the playground platform rocker of FIG. 8.

(Continued)

The broken lines on the drawings represent environmental structure and form no part of the claimed design.
